VISUAL PROOF TERMINAL FOR ALUMINUM WIRE CONDUCTOR

Ronald Clarence Hoffman, Williamstown, Pa., assignor to
AMP Incorporated, Harrisburg, Pa.

Filed Jan. 14, 1972, Ser. No. 218,042

Term of patent 14 years

The portion of the term of the patent subsequent to
June 12, 1987, has been disclaimed

Int. Cl. D13—03

U.S. Cl. D26—1 A

FIG. 1 is a perspective view of a visual proof terminal for aluminum wire conductor showing my new design;

FIG. 2 is a top plan view of the design shown in FIG. 1;

FIG. 3 is a side elevation of the design shown in FIG. 2;

FIG. 4 is a bottom plan view of the design shown in FIG. 3.

I claim:

The ornamental design for a visual proof terminal for aluminum wire conductor, as shown.
